UNITED STATES PATENT OFFICE.

JULIUS FERDINAND HEINRICH VOIGT AND JACOB ADOLF HAEFFNER, OF BOCKENHEIM, GERMANY, ASSIGNORS TO THE ROESSLER & HASLACHER CHEMICAL COMPANY, OF NEW YORK, N. Y.

ELECTRICAL RESISTANCE.

SPECIFICATION forming part of Letters Patent No. 617,375, dated January 10, 1899.

Application filed December 26, 1895. Serial No. 573,388. (No model.)

To all whom it may concern:

Be it known that we, JULIUS FERDINAND HEINRICH VOIGT and JACOB ADOLF HAEFFNER, subjects of the King of Prussia, Emperor of Germany, and residents of the city of Bockenheim, near Frankfort-on-the-Main, in the Kingdom of Prussia, German Empire, have invented certain new and useful Improvements in Electrical Resistances, (for which we have obtained Letters Patent in Belgium, No. 116,121, dated June 18, 1895, and in Italy, R. G. XXX, No. 39,072, R. A., Vol. LXXVI, No. 328, dated June 18, 1895,) of which the following is a specification.

This invention consists in an electrical resistance, of a thin layer of liquid metal applied by means of a firing process—after the manner in which lustrous gold, silver, or platinum decorations are applied—to an enamel layer on a suitable base-piece. The so-formed thin metal layer contains the metal in a very finely-divided state. It can be applied in solution, being painted on after the manner of applying the well-known metalliferous lusters or liquid-bright metal colors on an enamel layer, the metal being afterward brought out by a firing process, whereby the latter is obtained as an uninterrupted layer in the form of a band, strip, or the like. By "metalliferous lusters" or "liquid-bright metal colors" in this sense are understood a homogeneous solution of organic compounds of metals or precious metals—such as, for instance, sulfid of gold combined with balsam of sulfur or mixtures of the same in organic dissolvents, such as nitrobenzene, with or without addition of essential oils. These solutions may contain compounds of bismuth, boric acid, or phosphoric acid as combination of flux. As "precious metals" are to be understood not only gold, silver, and platinum, but also the elements of the platinum group—palladium, rhodium, iridium, osmium, and ruthenium. Aluminium can be used in the same manner.

The accompanying drawings illustrate a resistance of this description.

Figure 1 is a plane of resistance. Fig. 2 is a section along x x' .

On the base-plate a the layer of enamel is applied, and upon the latter the resistance-layer b , which is drawn forward and backward in a meandering or sinuous uninterrupted band, strip, or line of considerable length. For the purpose of conducting the electric current to or from the resistance either large aggregations of the resistance material are used or special metallic parts are arranged on the required places. Such an arrangement is exemplified on the drawings by the terminals c and d , which are soldered upon the ends of the metallic layer b .

The metallic layer, made in the manner described, finds its application especially in rheostats for incandescent lamps which are required to burn dimly at times and as a protecting device or safety-fuse for weak-current installations to protect them against strong currents, and, further, as heat-conductors for cooking and heating apparatus. In the latter cases the plate shown on the drawings is arranged in an entirely analogous manner conformable to the purpose as a jacket for cooking vessels or heating-pipes.

We claim—

1. An electrical resistance consisting of a suitable base-piece, an enamel-layer secured thereto, and a conducting-layer of fired liquid metal, substantially as specified.

2. An electrical resistance comprising insulating non-combustible material, and a conducting-layer of fired liquid metal, substantially as specified.

In witness whereof we have hereunto set our hands in presence of two witnesses.

JULIUS FERDINAND HEINRICH VOIGT.

JACOB ADOLF HAEFFNER.
